UPSETTING MECHANISM

Richard Lester Wilcox, Waterbury, Conn., assignor to The Waterbury Farrel Foundry and Machine Company, Waterbury, Conn., a corporation of Connecticut

Application January 26, 1932, Serial No. 588,859

20 Claims. (Cl. 10—12)

This invention relates to new and useful improvements in upsetting mechanism or the like.

It is the object of the invention, among other things, to provide means for presenting a blank successively to each of several stations for operations thereon, to eject the blank from each of such stations after such operations in timed relation with such means, and to be engaged and carried thereby, as well as means for releasing 10 for escape the finished product. Another feature of the invention is to adapt this mechanism for use with either a single blow and/or solid die header of a conventional type, whereby the adaptability and extent of use of such machines 15 may be materially increased.

To these and other ends, my invention consists, among other things, in the new and improved upsetting mechanism, having certain details of construction and combinations of parts, 20 as will be hereinafter described and more particularly pointed out in the claims.

Heretofore, in subjecting a blank to successive operations in a header or the like, the blank is held in a fixed position in relation to the die, and 25 punches of various forms and types are successively presented thereto. Such method requires the use of a plural blow header or the like. As plural blows are required while the blank is held in a fixed position, a reduced output results over headers, or the like, of the single 30 blow type.

In this improved device, plural solid dies and punches are used and the blank is transferred from one die to another so that a single blow 35 header may be used instead of a plural blow. At each station an operation is performed at each stroke of the gate so that a completed product results from each forward movement of the gate. In the plural blow type, a finished product results only at the termination of each series of 40 blows, which requires a reciprocation of the gate for each blow.

With this improved mechanism, the punch holder is not moved transversely of the movement 45 of the gate, except for adjustment purposes, thus eliminating all of the punch holder moving mechanism.

The arrangement of the punches and dies is 50 also such that they are in substantially a straight line and substantially parallel with the axis of the crank shaft, through and from which the gate is actuated. Therefore, a machine having great strength without tendency to torsional and other objectionable strains, results, ensuring the 55 utilization of a header of smaller size than would

otherwise be necessary, and having a longer operative life.

Further, in this invention, the blank is cut from a rod length, and while in the cutter, as is the practice, is transferred to a station, and thereafter, to successive stations by transfer mechanism, shown herein as actuated in part by the cutter mechanism. This utilizes a present and required motion for the transfer mechanism and avoids the use of additional parts to produce 10 the same result.

The fingers of the transfer mechanism are opened by parts associated with the gate, thus also utilizing another present and required motion without additional parts. Thus, the 15 motions of both the cutter and gate mechanisms are utilized for the transfer mechanism.

At the stations the blank is ejected from the tools by synchronously actuated knockout mechanism that presents the blanks into position 20 where they are grasped by the transfer fingers before the latter close, on the return movement of the gate.

The knockout mechanisms are arranged so that the length of stroke thereof may be varied 25 according to the requirements of each station.

There are other new and novel features about this invention that will appear from the following description and the accompanying drawings, and are more particularly pointed out in the claims. 30

Referring to the drawings, in which like numerals of reference indicate like parts in the several figures;

Figure 1 is a fragmentary view of a single blow header, upsetting machine or the like, with 35 the improvements herein set forth associated therewith;

Figure 2 is another view thereof;

Figure 3 is an enlarged fragmentary transverse sectional view, the parts in section being taken 40 generally upon line 3—3 of Figure 1;

Figure 4 is an enlarged fragmentary view of a portion thereof, the parts in section being taken generally upon line 4—4 of Figure 1;

Figure 5 is a fragmentary view of the gate, die 45 holder and other parts, the parts in section being taken generally upon line 5—5 of Figure 6;

Figure 6 is a view of the transfer mechanism and adjacent parts, those in section being taken 50 generally upon line 3—3 of Figure 1;

Figure 7 is a sectional view of the feed bracket, the parts in section being taken generally upon line 7—7 of Figure 1;

Figure 8 is a form of mechanism, other than 55

shown elsewhere, for opening the transfer fingers; and

Figure 9 is a view of the finger release mechanism.

As hereinbefore indicated, this improved mechanism is particularly adapted for association with a solid die and/or single blow header, upsetting machine or the like. Its use enlarges the adaptability of such headers for work not heretofore possible to be done thereon, but only with headers having plural blows.

In the mechanism herein shown there are plural punches or other tools, which co-operate with dies or other tools; a punch and die-co-operating to perform one of the cycles of operations at each movement of the gate. Thus, at each forward movement of the gate each punch and die performs an operation, all combining to develop and produce the finished product, one of which is produced and released at each movement of the gate.

As the punches maintain a fixed position in relation to the gate, none of the mechanism associated with the gate in plural blow headers is required. So far as at present advised no one has heretofore applied plural blows to a blank in a single blow header, or discovered the possibility of doing so without moving the punches transversely of the movement of the gate.

In the embodiment of the form of the invention disclosed herein the header, upsetting machine, or the like, is of the conventional type.

Referring to the drawings, 10 indicates the body member of the header; 11 the crank shaft rotatably mounted therein having driving wheels 12 upon opposite ends thereof; 13 the gate which is slidably mounted in the body member beneath the caps 14; 15 the pitman that connects the gate with the crank shaft; and 16 is a shaft that is journaled in the body member and is driven from the crank shaft by the gear 17 and pinion 18.

Fixed upon one side of the body member is a cut-off bracket 19, within which is slidably mounted the cut-off plate 20, and actuated in part thereby is the cutter bar 21, which moves in a path substantially parallel with the axis of the crank shaft. Connected with this cutter bar is a plate 22, in which is fixed a stud 23 carrying a cam roll 24. This cam roll contacts with the cam plate 25 connected with the cut-off plate 20 to move the cutter bar in one direction and in the opposite direction by the cam plate 26, through a cam roll 27 on the stud 23.

Relative adjustment of the position of the cutter bar 21 is obtained through an adjusting screw 28, which is threaded through the stud 23. The outer movement of this cutter bar is limited by a stop screw 29.

The cut-off plate 20 derives a reciprocatory motion from a crank 30 on the shaft 16 through the pitman 31 and turn buckle mechanism 32.

The cut-off mechanism above described is of the conventional type and the details of its construction and operation are now well known in the art.

Fixed to the forward end of the gate 13 is a backing plate 33 and adjustably mounted thereon are a plurality of punch holders 34, 35, 36 and 37. With each of these punch holders are associated bolts 38 and 39, the former of which is encircled by a block 40 slidable in the slots 41 in the punch holder, and the bolt 39 being adjustable within the slot 42 in the backing plate 33.

By this mechanism a limited variable adjustment of the punch holder relatively to the gate is permissible, and in its several adjusted positions is maintained by the nuts upon the bolts 38 and 39 and the screw 43 threaded through the punch holder and impinging against a stationary part.

In each punch holder is mounted an operating tool, and as shown, these are designed for the fabrication of a rod length into nuts.

In the holder 34 is a pressure punch 44 mounted within a bushing 45 and the inner end of which abuts against a backing plate 46, this in turn being in contact with the forward end of a backing plug 47.

In the punch holder 35 is an upsetting punch 48, the inner end of which abuts against a backing block 49, and in contact with the forward end of a backing plug 47. Mounted within the upsetting punch 48 is the ejector pin 50, actuated in one direction by a coil spring 51.

In the punch holder 36 is an upsetting punch 52, supported by a backing block 53, which likewise engages the forward end of a backing plug 47. The outer ends of the punches 48 and 52 are shaped to upset the metal of the blank into predetermined shapes, the former being a primary shape and the latter the final shape of the blank.

While I have shown two upsetting punches herein, in another form of article, or even in the same type of article, a single punch might be sufficient, or a greater number than two.

As the nut produced by the tools herein is hexagonal in shape, the forward end 54 of the punch 52 is substantially hexagonal in cross section.

In the punch holder 37 is a piercing punch 55 supported in a bushing 56, which abuts against a backing plate 57, and the latter against the backing plate 33. As shown, there are four separate and independent punch holders, but the number thereof may be greater or less, if desired.

Each backing plug 47 is angular at the rear end and contacts with a wedge 58 mounted on a wedge block 59 that is adjustable in the gate at substantially a right angle to the axis of the backing plug 47 and held in adjusted positions by a screw 60, in a well known manner. By means of the wedge blocks the extreme outward position of the face of each tool is accurately determined and in such position permanently held.

Projecting forwardly on each punch holder is a lug 61, within which the tool is supported, and on the top and bottom thereof at its forward end are secured the plates 62, upon each of which is a cam face 63. The cam plates associated with the punch holder 34 extend laterally thereof, substantially as shown in Figure 4.

Mounted in a recess in the wall of the pocket 129 in the body 10, opposite the gate, is a backing plate 64, and associated therewith is a die holder 65, which is secured in position by a locking wedge 66 held by a bolt 67 in a well known manner.

Within the die holder 65 are a plurality of dies or tools that are positioned, except for the cutting-off tool, substantially concentric with the tools associated with the gate.

The tools mounted in the die holder are the cut-off die 68, the squaring die 69, upsetting dies 70 and 71, and the piercing die 72. Each of the dies 68, 69, 70 and 72 engages backing blocks 73 that contact with the backing plate 64.

Letters Patent Nos. 1,832,167 and 1,832,168, issued November 17, 1931, disclose a set of tools similar to those herein shown, with the exception

of the punch 44 and die 69. The latter are designed to square the ends of the blank if this seems desirable. The punch 48 and die 70 upset the blank to dome shape.

5 The die 71 is mounted in a sleeve 74 and held in its outward position by the tension of the spring 75. Within the die sleeve 74 and projecting through the opening in the die 71, is a combined pressure and knockout pin 76, which is moved against the resistance of the spring 77. 10 The cross sectional shape and area of the opening in the die 71 is substantially the same as that of the punch 54.

Within the backing plate in the rear of the 15 piercing die 72 is a pin 78, the forward end of which projects over an opening 79 through one side of the die 72.

20 Fixed to the die holder 65 is a stripper plate 80 having an opening 81 therethrough slightly larger than the diameter of the piercing punch 55, which projects therethrough in its forward position.

25 The relative vertical position of the die block 65 is maintained by the set screw 89 and the dies are held rigid by the screws 90 or the like.

Fixed to one wall of the pocket 129 is a bracket 82, which supports a stop pin 83 that is adjustable axially therein by means of the nuts 84.

30 Secured to the inner end of the cutter bar is a cutter 85, having spring fingers 130 associated therewith, substantially as shown in Figure 6. This cutter and the spring fingers are of the conventional type, as well as their method of association with the cutter bar.

35 In operation a rod is advanced by means of the feed rolls 86 through the cut-off die 68 until the end thereof abuts against the stop pin 83. The cutter bar now moves forward and the cutter 85 severs that portion of the rod between the stop pin and the face of the cut-off die. This cut-off portion, now the blank, is carried by the cut-off knife and spring fingers to a position where it is in front of the opening in the die 69 with its axis concentric with that of the punch 44. The forward movement of the gate projects the blank 40 into this opening in the die 69 and against the end of the knockout rod 87. The pressure applied to the blank squares the ends thereof so that they are at substantially a right angle to the axis of the blank.

50 Some metals do not cut off squarely but at an angle to the axis of the blank. Such angular or non-square ends do not impair subsequent operations on the blank, except in certain classes of work. Hence, the use of the die 69 and punch 44 may be unnecessary at times.

55 After leaving the die 69, the blank is presented to the die 70, where it is domed in substantially the manner shown in the above referred to patents, and ejected therefrom by the ejector pin 59 and knockout rod 88. Thereafter, the blank is presented to the die 71 and the dome shape blank is compressed between the knockout pin 76 and punch 54 and the thickness and outside shape of 60 the finished article determined.

65 The blank, which has now assumed the form of a nut, is presented in front of the die 72 and inside of the stripper plate 80, and the punch 55 pierces a hole therethrough. The slug formed thereby is deflected downwardly through the opening 79 in the die by an angular end face on the pin 78 and falls into a receptacle conveniently arranged to receive it. As the gate recedes, the finished nut is stripped from the punch by the 70 stripper plate 80, and the completed nut or article 75

drops into a chute which leads to a receptacle conveniently arranged to receive the same. At each forward stroke of the gate four different operations are performed upon the blank, by separate sets of tools to produce the finished nut 5 or article. These successive operations allow for a proper and convenient flow of the metal in the blank without distortion or rupture thereof.

The article produced by the tools herein is a completed nut, ready for threading, that is 10 formed from a rod of metal and with the minimum waste of material and without requiring a subsequent finishing of the exterior thereof.

Obviously, as before indicated, the shape of the tools may be varied to produce rivets, bolts, 15 screws, and the like, as well as many other varying shapes and sizes.

The tools are arranged so that they are in substantially the same plane as the axis of the crank shaft, thus obtaining the maximum pressure and eliminating torsional strains.

20 The knockout rods 87, 88 and 91 are operated synchronously so as to eject all of the blanks from the dies at one and the same time, to be taken up and carried by the transfer means. 25 The mechanism for actuating the knockout rods comprises in part, a plurality of rock levers 92, one for each of the rods, which contact therewith substantially as shown in Figure 1. These are mounted upon a shaft 93 in the feed bracket 30 94 and the rolls 95 thereon ride against the cam shoe 96 on the rock lever 131, fixed on the shaft 97. The cam shoe 96 is of harder metal than the rock lever and may be replaced by a new shoe if wear or other reasons should demand.

35 Shaft 97 derives an oscillating movement in timed relation with other parts from companion cams 98 and 99 mounted upon the shaft 96, through a link 100, connected at one end to a crank 101 on the shaft 97 and at the other end 40 to a rock member 102. This rock member is actuated by the cam 99 through a cam roll 132, which rides against the cam face. A similar rock member 103 is actuated by the cam 98 through a cam roll 104, which rides against the cam face. 45 These rock members are flexibly connected by the rod 105 having a spring 106 therearound. Thus, the rock shaft 97 is operated positively in both directions by cam mechanism which insures a proper timed relation movement of the 50 rock levers 92 and knockout rods with the punches. The screws 107, threaded in the bracket 94, adjustably limit the movement of the rock levers 92 when pushed outwardly by the knockout rods when a blank is projected into a die.

55 The transfer mechanism is associated with the cutter bar and moves therewith. It comprises in part two slide members 108, which move within grooves in the face of the die holder 65, and are connected with each other and with the cutter 60 bar by the cross bar 109.

Fixed in each slide member are a plurality of studs 110, upon each of which is rotatably mounted a transfer finger 111, the inner ends 65 112 of which are suitably shaped to grasp the blank at one of the stations and carry it to the next station. The transfer fingers are moved toward each other by the springs 113 connected at one end with the fingers and at the other end to the fixed stops 114, in each of which is an adjustable stop screw 115 which limits, to predetermined positions, the inward position of the gripping end of the fingers. On each finger between its fulcrum point on the stud 110 and the gripping end thereof, is a rounded end stud 116, 70 75

which projects into the path of the cam faces 63 on the cam plates 62.

When the gate is in its rear position, that is, away from the face of the dies, the springs 113 will hold the fingers in their innermost position, with their inner ends 112 substantially in the position shown in Figure 3. As the gate moves forward the cam plates 62 engage the rounded ends of the studs 116 and force the fingers outwardly. Their extreme outward position is shown in Figure 6. The extent of the opening is determined by the cam face 63 on the plate 62 when in engagement with the stud 116.

In order that it may not be necessary to substitute new fingers complete for each different shape blank, a separable tip 117 may be used and attached in any convenient manner to the body of the finger. Thus, the gripping face of each finger may be varied at will.

Another form of contact mechanism between the transfer finger and the punch holder is shown in Figure 8, wherein a stud 137 is substituted for the stud 116, in the outer end of which is a ball 134, positioned and in part held against dislodgment by the screw 135. This form of device will minimize friction and obviate wear of the parts.

The timing of the parts is such that the blanks at the several stations are ejected from the dies simultaneously and pushed into position between the fingers when the same are closing, by the withdrawal of the gate. Thus, a blank, in its incompletely formed, is carried from one station to another until its arrival at the station where it is completed by the piercing operation. The remaining end of the rod length, after it has been successively presented to the cut-off knife, may not be sufficiently long for a new blank. Such short length is, however, advanced through the cut-off die by the new rod length, the forward end of which supplies sufficient material to make a full length blank. Thus, in the cutter there may be two short rod pieces which combined make a single length blank. These two pieces may go through the entire subsequent operations without disturbing any tools or parts but producing, however, a faulty article.

To prevent this, as well as any damage that might result to the tools, or other parts, by either a short piece getting out of alignment, or otherwise, means have been provided to release such short pieces so that they will not be presented for subsequent operations. Such means has for its object an independent movement of the lower transfer finger near the cutting off station, so that the two short pieces will not be engaged thereby and drop out of the machine.

This mechanism comprises a drum 118, mounted upon a stud 119, in a bracket 136, having a cable connection 120, with a stud 121 associated with the lower transfer finger adjacent to the cut-off knife. A similar cable 122 connected with the drum 118 passes over an idler 123 mounted on a fixed bracket 124, and connected with a treadle 125 of a well known type.

The ends of cables 120 and 122 are connected with the drum by screws 126 or the like, whereby the length of the cables may be varied for adjustment.

A spring 127 between the drum 118 and a fixed part insures the drum being held in such position that there is no pull on the transfer finger 78 through the cable 120 except when pressure is

applied through the treadle 125. A spring 128 between the cable 122 and treadle 125 provides means to take up any excess movement of the treadle after the transfer finger has been moved to its extreme position.

As the end of the old and the new rod lengths are moved into the path of the cut-off knife, the operator presses the treadle 125 downwardly, the transfer finger is moved to its non-gripping position, and the short ends of the old and new rod lengths cut therefrom drop out of the machine because not engaged by the transfer fingers.

All the other transfer fingers perform their function, however, and transfer the blanks as usual.

After the forward end of the new rod length has been subjected to the first cut-off operation, the operator releases the treadle 125. The returned transfer finger is released and returns to its gripping position and performs its transfer function as before.

Having thus described one embodiment of the invention, it is obvious that numerous and extensive departures may be made therefrom without departing from the spirit of my invention, and within the scope of the appended claims.

What I claim is:

1. In mechanism of the character described, a plurality of dies, a plurality of punches co-operating therewith, one or more punch holders for the punches, a cam plate on each punch holder, and transfer means, having fingers as a part thereof, for carrying the blank successively to the dies and having an element thereon in the path of movement of the cam plate, whereby the fingers are moved to their non-gripping positions.

2. In mechanism of the character described, a plurality of dies, a plurality of punches co-operating therewith, one or more punch holders for the punches, and transfer means, having fingers as a part thereof, for carrying the blank successively to the dies and having an element thereon in the path of movement of the punch holder, whereby the fingers are moved to their non-gripping positions, said element having a ball contact surface.

3. In mechanism of the character described, a gate, a plurality of solid dies, a plurality of punches cooperating therewith, means for cutting off a blank from a rod length, transfer means, having fingers on a part thereof, for carrying the blank successively to the dies, means on the gate for moving the fingers to their non-gripping positions; and means for ejecting the blanks from the dies while the fingers are actuated by the gate means.

4. In a heading machine, a gate, a plurality of tools, means for cutting off a blank from a rod length, means for transferring such blank successively to the tools, comprising a slide, a connection between the slide and the cut-off means, a plurality of fingers associated with the slide and movable toward each other to grip the blank therebetween, each finger having a surface thereon in the path of movement of the gate, and a part associated with the gate that engages the said surface and moves the fingers to their non-gripping positions.

5. In a header, having a pocket in the body thereof; a gate movable into and out of the pocket; a plurality of punches carried by the gate; a cutter device projecting through one wall of the

5 pocket; a die holder secured to that wall of the pocket opposite the gate; a plurality of dies in the die holder, the axes of some of which are coincident with the axes of the punches; means for transferring a blank, from the cut-off device, successively to the dies and in line with the punches, comprising in part movably mounted fingers, that hold the blanks in line with the dies; and means on the gate adjacent to the 10 punches that actuate the fingers so as to release their hold upon the blank as the punches are about to engage therewith.

6. In a heading machine, a plurality of sets of tools; means for cutting off a blank from a rod 15 length; and means for transferring such blank successively to the sets of tools, comprising a slide; a connection between the slide and the cut-off means, a plurality of fingers associated with the slide and movable toward each other to 20 grip the blank therebetween, each finger having a part thereon in the path of movement of the gate; and means associated with the gate for engaging said part and moving the transfer fingers positively in one direction.

25 7. In a heading machine having a gate, a plurality of sets of tools, a portion of which are on the gate; means for cutting off a blank from a rod length; and means, operated in part by the cut-off means and by parts on the gate, for transferring such blank successively to the sets of tools.

30 8. In a device of the character described, wherein a rod length is intermittently advanced, the combination with means for cutting off a 35 portion of such rod length, a series of tools, a transfer device for moving the blank from the cut-off station to the tools, and means for independently actuating the transfer device whereby it will become inoperative in part for transfer 40 purposes.

45 9. In a device of the character described, wherein a rod length is intermittently advanced, the combination with means for cutting off a portion of such rod length, a series of tools, a transfer device for moving the blank from the cut-off station to the tools, comprising in part transfer fingers that engage the blank, arranged in pairs, and means for independently actuating one of the transfer fingers, whereby it will be 50 moved into and held in a non-gripping position and thereby made inoperative.

55 10. In a device of the character described, wherein a rod length is intermittently advanced, the combination with means for cutting off a portion of such rod length, a series of tools, a transfer device for moving the blank from the cut-off station to the tools, and means for independently and manually actuating the transfer device, whereby it will become inoperative in part 60 for transfer purposes.

65 11. In a device of the character described, wherein a rod length is intermittently advanced, the combination with means for cutting off a portion of such rod length, a series of tools, a transfer device for moving the blank from the cut-off station to the tools, means for independently actuating the transfer device, whereby it will become inoperative in part for transfer purposes, comprising a drum, a connection between the 70 drum and one of the transfer fingers, and manual means for rotating the drum.

75 12. In a header having a pocket in the body thereof; a gate movable into and out of the pocket; a plurality of punches carried by the gate; a plurality of solid dies secured to that wall

of the pocket opposite the gate, the axes of some of which are coincident with the axes of their co-operating punches; a cutter device projecting through one wall of the pocket and movable in a plane extending across the face of the dies, 5 for cutting off a portion of a rod projecting beyond the face of one of the dies and transferring such cut-off portion, now a blank, into register with the next succeeding die and its co-operating punch; and means, connected and movable with the cutter device, for thereafter transferring the blank, from the aforesaid position, successively to the other dies and in line with their co-operating punches.

13. In a heading machine; a cut-off die; a plurality of sets of tools located in substantially the same plane; means that includes a cutter bar, or the like, for cutting off a projecting portion of a rod length passed through a cutting die; means connected and movable with the cutter 20 bar for grasping and transferring such cut-off portion, now a blank, successively from one set of tools to the next succeeding set of tools, comprising in part a slide secured to the cutter bar, and a plurality of fingers associated with the 25 slide and movable toward and away from each other to grip a blank therebetween.

14. In a heading machine; a cut-off die; a plurality of solid dies; a plurality of punches co-operating with the solid dies; a slide movable in 30 a plane substantially parallel with the face of said dies; a cutter connected and movable with the slide; means for imparting movement to said slide during which the cutter will sever a portion of a rod length projecting beyond the face of the 35 cut-off die; one or more pairs of members connected and movable with said slide; a finger connected with each of said members and movable toward and away from each other to grasp said cut-off portion, now a blank, and carry the 40 same successively from said solid dies to another of said dies and hold the same in register with its co-operating punch until it has been projected thereby into the dies.

15. In a heading machine; a cut-off die; a plurality of dies; tools or the like co-operating with said latter dies; a slide movable in a plane substantially parallel with the face of said dies; a cutter connected and movable with the slide; means for imparting movement to said slide, 50 during which the cutter will sever a portion of a rod length projecting beyond the face of the cut-off die; a support element fixed to the slide and projecting in advance of the cutter end thereof; and fingers connected with said element 55 and movable toward and away from each other to grasp said cut-off portion, now a blank, in advance of the cutter, and carry the same successively from one of said dies to another of said dies and hold the same in register with its co-operating tool until the blank has been projected into the die.

16. In a heading machine; a cut-off die; a plurality of dies; tools or the like co-operating with said latter dies; a slide movable in a plane 65 substantially parallel with the face of said dies; a cutter connected and movable with the slide; means for imparting movement to said slide, during which the cutter will sever a portion of a rod length projecting beyond the face of the cut-off die; a support element fixed to the slide and projecting in advance of the cutter end thereof with a portion thereof upon one side of said dies and another portion upon the opposite side of said dies; and fingers connected with each por- 75

tion of said element and substantially opposite each other and movable toward and away from each other to grasp said cut-off portion, now a blank, in advance of the cutter, and carry the 5 same successively from one of said dies to another of said dies and hold the same in register with its co-operating tool until the blank has been projected into the die.

17. In a heading machine; a cut-off die; a 10 plurality of dies; tools or the like co-operating with said latter dies; a slide movable in a plane substantially parallel with the face of said dies; a cutter connected and movable with the slide; means for imparting movement to said slide, during which the cutter will sever a portion of a rod length projecting beyond the face of the cut-off die; a support element fixed to the slide and projecting in advance of the cutter end thereof; fingers connected with said element; 20 yielding means for actuating the fingers in one direction, whereby to grasp said cut-off portion, now a blank, in advance of the cutter, and carry the same from one of said dies to another of said dies and hold the same in register with its co- 25 operating tool until the blank has been projected into the die; and independently actuated means for moving all of the fingers in the opposite direction, whereby to release the hold of said fingers on the blank.

18. In a machine for making bolt blanks and the like, a plurality of stationary tools equally spaced in transverse alignment, a plurality of reciprocating tools in similarly spaced transverse alignment, means for reciprocating said latter tools simultaneously, means for feeding stock one 35 step for each reciprocation of said tools, said feeding means being spaced from the first pair of tools a distance equal to the transverse spacing of successive pairs of tools, a cut-off blade trans- 40 versely reciprocable for cutting off a length of stock and moving it into position between the first pair of tools, transfer mechanism movable with said blade adapted to receive a blank from said first pair of tools and move it into position 45 between the second pair of tools, said mechanism comprising work gripping fingers, and means for

holding said fingers separated during the return movement of the cut-off blade and transfer mechanism.

19. A machine for simultaneously conducting a plurality of steps of a blank forming procedure 5 which includes, a plurality of dies, a plurality of shaping tools, each of said tools being adapted to cooperate with one of said dies for producing a change of shape in a blank in accordance with a step in the forming procedure; a transfer mechanism for moving a blank from a position adjacent one die to a position adjacent another, said transfer mechanism having independently actuated fingers for gripping each blank to be moved, means for relatively and simultaneously 15 moving said dies and said tools into a blank forming relationship with respect to each other, and means for moving the fingers relatively to the other parts of the transfer mechanism and opening said fingers out of the path of the forming 20 tools and holding them in an open relationship immediately prior to the forming operation.

20. A machine for conducting a blank forming procedure which includes, a die, a tool, said tool being adapted to cooperate with said die for producing a change of shape in a blank in accordance with the forming procedure, means for moving said tool to and from a cooperative relationship with respect to said die, a cut-off die; a reciprocating transfer mechanism for holding 30 a blank and moving it to said die from the cut-off die, said transfer mechanism including a pair of slides, a pair of bell cranks pivotally mounted thereon with their free ends in substantial engagement with each other when in their closed position at a point between said slides, resilient means for normally holding said fingers in a closed relationship with respect to each other, a post mounted on each of said bell cranks and projecting outwardly and laterally therefrom, said tool having plates mounted thereon for cooperating with the posts of the transfer mechanism for opening said fingers and releasing the blank immediately prior to the actual forming operation.

RICHARD LESTER WILCOX.
